UNITED STATES PATENT OFFICE.

DAVID NEWTON WALLER, OF SYLVAN, WISCONSIN.

DESIGN FOR A LID-LIFTER.

SPECIFICATION forming part of Design No. 22,329, dated April 4, 1893.

Application filed February 13, 1893. Serial No. 462,201. Term of patent 7 years.

To all whom it may concern:

Be it known that I, DAVID NEWTON WALLER, a citizen of the United States, and a resident of Sylvan, (Boaz P. O.) Richland county, State 5 of Wisconsin, have invented and produced a new and original Design for Lid-Lifters, of which the following is a specification, reference being had to the accompanying drawings, wherein—

Figure 1 is a side elevation of a lid lifter of my design. Fig. 2 is a plan or upper edge view of the lid lifter shown in Fig. 1, illustrating other features of the design. Fig. 3 is a cross section of Fig. 1.

15 The leading features of my design consists in a base having front and rear tongues tapering slightly toward their tips which latter are approximately flat, said base having semi-octagonal sides above which are dished shoulders at the junction of the base and handle, and the latter is also of the construction shown and described.

25 The base A has semi-octagonal sides B, above each of which is a dished or inwardly curved shoulder C, and the handle H extends into this base at the upper extremity of said shoulders. From the front and rear of the base extend tongues T T' which are practical duplicates. Each tongue has its sides cut away 30 as shown at D whereby they taper slightly from said semi-octagons to the outer ends or extremities E of the tongues, which extremities are approximately flat. The lower faces F of the tongues curve slightly upward transversely of the tongues, and said faces also 35 rise on gentle curves from the extremities of

the tongues to the center of the base where they unite in a groove or obtuse angle G, which angle extends completely across the base and through the diameters of said semi-octagonal sides. 4c

The handle H of this design of lid-lifter has flat sides, while its upper end and its upper and lower edges are slightly rounded transversely, and this transverse rounding is continued from the handle down past the base and out the length of the tongues to their extremities. Through said handle at the upper end is a slot L whose walls are parallel with the edges of the handle and slightly beveled 45 at their corners, the slot tapering from its upper end, which is rounded as at J, to its lower end K where it forms an acute angle. Near the longitudinal center of the handle are projections L L' located on the upper and 50 lower edges opposite each other and forming obtuse angles. Farther down and on the upper edge of the handle is a downwardly facing shoulder M. From this shoulder the handle curves slightly downward and joins the 55 base A. 60

What I claim is—

The design for lid-lifters, substantially as herein shown and described.

In testimony whereof I have hereunto subscribed my signature on this the 8th day of February, A. D. 1893. 65

DAVID NEWTON WALLER.
